DESIGN FOR A COMBINED SCREW DRIVER AND WRENCH

Willis E. La Rue, Indianapolis, Ind.

Application July 19, 1938, Serial No. 78,586

Term of patent 14 years

To all whom it may concern:

Be it known that I, Willis E. La Rue, a citizen of the United States, residing at Indianapolis, in the county of Marion and State of Indiana, have invented a new, original, and ornamental Design for a Combined Screw Driver and Wrench, of which the following is a specification, reference being had to the accompanying drawing, forming part thereof.

Figure 1 is a perspective view of a combined

screw driver and wrench showing my new design, and showing the wrench portion in closed position.

Figure 2 is a view similar to Figure 1 but showing the wrench portion in open position.

I claim:

The ornamental design for a combined screw driver and wrench, as shown and described.

WILLIS E. LA RUE.
